UNITED STATES PATENT OFFICE.

LOUIS H. SOISSON, OF SCOTTDALE, PENNSYLVANIA, ASSIGNOR OF ONE-HALF TO
EUGENE F. SOISSON, OF LATROBE, PENNSYLVANIA.

HEDGE-TRIMMER.

1,192,699.

Specification of Letters Patent. Patented July 25, 1916.

Application filed October 28, 1915. Serial No. 58,448.

To all whom it may concern:

Be it known that I, Louis H. Soisson, a citizen of the United States, residing at Scottdale, in the county of Westmoreland 5 and State of Pennsylvania, have invented certain new and useful Improvements in Hedge-Trimmers, of which the following is a specification.

This invention relates to garden implements or tools and more particularly to a 10 novel hand operated instrument for trimming hedge plants.

To this end, the invention contemplates a simple and practical cutting tool that may 15 be conveniently held in one hand, and manipulated by the other with ease and facility in substantially the same manner as a pair of shears.

In this connection, the invention also has 20 in view a device that may be easily moved and guided over a hedge growth to clip or trim the same, while at the same time owing to the character of the cutting blades being especially adapted to cut a maximum 25 surface with accuracy and rapidity.

Another object of the invention is to provide a device of this character wherein the cutting instrumentalities have a free sliding movement through the utilization of simple 30 and substantial operating connections which reliably perform their functions and which may be provided at a minimum expense and easily kept in working order and condition with little or no difficulty.

35 With the above and other objects in view which will more readily appear as the nature of the invention is better understood, the same consists in the novel construction, combination and arrangement of parts herein- 40 after more fully described, illustrated and claimed.

A preferred and practical embodiment of the invention is illustrated in the accompanying drawings, in which—

45 Figure 1 is a plan view of the instrument in its normal position. Fig. 2 is a plan view in its open position. Fig. 3 is a horizontal sectional view on the line 3—3 of Fig. 1. Fig. 4 is a transverse sectional view 50 on the line 4—4 of Fig. 1.

Similar reference characters designate corresponding parts throughout the several figures of the drawings.

A novel and distinctive feature of the 55 present invention is to provide an implement

of the character set forth wherein one handle member may be held still while the other is moved to operate the cutting blade. Accordingly, as will be obvious from Fig. 1, the device embodying this novel feature 60 essentially includes a rigid body member 1 having rigidly secured thereto as indicated at 2, a fixed handle member 3 which affords a convenient means whereby the entire device may be supported when in use. This 65 body portion 1 is provided with a saw-tooth cutting edge 4, and at the edge opposite the cutting teeth is provided with a longitudinally extending strip 5 which is secured to the body by the fastenings 6 and provided 70 with the guideway 7 for receiving the back edge of a reciprocating cutter blade 8. This reciprocating cutter blade is therefore free to slide on the body or back member 1, and is provided with cutting teeth 9 which 75 coöperate with the cutting teeth 4 of the back. In addition to being guided on the back member 1 in the guideway 7, the said reciprocating cutter blade may be also guided by the upstanding pins 10 carried by 80 the back and projecting through the longitudinally disposed slots 11 in the cutter blade. These pins 10 may be provided with suitable clamping nuts 12 as shown to maintain the cutter blade in close sliding relation 85 to the back, and thereby secure a maximum cutting efficiency.

The end of the cutter blade 8 adjacent the handle portion of the device has secured thereto an operating link 13, which is provided with an angular foot portion 14 having a slot 15 which is disposed substantially transverse of the back member 1. This slot 15 receives an upstanding pin 16 carried by the angular portion 17 of the movable 90 handle designated in its entirety as 18. This handle member which includes a hand grip and the angular portion 17 swings on a pivot 19, located at the extremity of the said angular portion. This point may be also 95 utilized as means for rigidly fastening the fixed handle 3 to the back or body 1. Thus, as the handle 18 is reciprocated or swung on its pivot 19, it will be clear that the cutter blade 8 is given a reciprocating motion over 100 the back 1 so that the teeth 9 thereof cross the teeth 4 of the back to thereby effect the cutting action. Accordingly, it will be clearly apparent that the present device may 105 be readily grasped in one hand by the 110

handle 3, and operated with the other hand by grasping and manipulating the handle 18, to thus move the cutter blade 8. Owing to the special construction of the connections 5 between the movable handle 18 and the reciprocating cutter blade, the latter will have a free sliding movement.

From the foregoing, it is thought that 10 operation and many features and advantages of the present invention will be readily apparent without further description, and it will of course be understood that various changes in the form, proportion, and minor details of construction may be resorted to 15 without departing from the spirit of the invention, or scope of the appended claim.

I claim:

A hedge trimmer comprising a rigid back member having a plurality of cutter teeth 20 and guide means, a fixed handle carried by said back member, a reciprocating cutter

blade also having a plurality of cutter teeth carried upon said back member and working in the guide means thereof, and a movable handle having an angular end portion the 25 extremity of which is pivoted to the face of the back member, a pin carried by said angular end portion, and a relatively narrow extension member carried by the end of said reciprocating cutter blade and having 30 an angular end, said member being arranged to provide a working clearance for the angular end of the movable handle, and the angular end thereof having a slot for receiving said pin. 35

In testimony whereof I hereunto affix my signature in the presence of two witnesses.

LOUIS H. SOISSON.
